UNITED STATES PATENT OFFICE.

EDWARD C. BERNERS, OF TWO RIVERS, WISCONSIN.

GLUE AND MUCILAGE PENCIL.

1,223,360.

Specification of Letters Patent. Patented Apr. 24, 1917.

Application filed August 21, 1916. Serial No. 116,090.

To all whom it may concern:

Be it known that I, EDWARD C. BERNERS, a citizen of the United States, and resident of Two Rivers, in the county of Manitowoc and State of Wisconsin, have invented certain new and useful Improvements in Glue and Mucilage Pencils; and I do hereby declare that the following is a full, clear, and exact description thereof.

10 The present invention relates to new and useful improvements in devices for distributing mucilaginous or other fluids, and is more particularly directed to the provision of a glue and mucilage pencil of the general 15 type embodied in the Reissue Patent 14,115 issued April 18, 1916, and comprising a reservoir which has a distributing hood at one end which is surrounded by a protective handle casing from which said reservoir is 20 removable to permit immersion of the reservoir in hot water to reduce the viscosity of the fluid therein, the mucilage pencil embodied in said reissue patent, however being 25 adapted for use only in connection with one filling of fluid in the reservoir, and being discarded upon emptying the reservoir.

It is primarily the object of the present 30 invention to provide a glue pencil which is of a permanent nature, and which is provided with means whereby it may be readily filled more particularly without disturbing the attachment of the distributing member of the pencil to the reservoir.

The present pencil comprises, as in the 35 said previous patent, a reservoir and a protective casing surrounding the reservoir, and it is more particularly an object of the invention to provide means for positively securing the reservoir in the casing.

40 A further object resides in the provision of a locking means for the closure of the filling end of the outer casing which serves also, when the said closure is removed, to frictionally hold the reservoir with respect 45 to the casing whereby its accidental detachment therefrom is prevented, and further whereby the reservoir may be held in a partially projected position with respect to the casing to facilitate the proper refilling of the 50 reservoir.

A still further object resides in the provision of a closure member for the filling end of the reservoir which is held against possible accidental displacement by the closure

member of the adjacent end of the protective 55 casing.

A still further object resides in the provision of an arrangement whereby the attaching portion of the distributing hood to the reservoir is shielded by the adjacent end 60 of the casing, to procure a neat and attractive appearance of the pencil.

With the above and other objects and advantages in view, the invention resides more particularly in the novel combination, arrangement and formation of parts more particularly hereinafter described and pointed out in the appended claims.

In the drawings.

Figure 1 is a side elevational view of a 70 glue and mucilage pencil constructed in accordance with the present invention, the end portions being broken away more clearly disclosing the structure thereof.

Fig. 2 is a transverse sectional view 75 through the filling end portion of the pencil, as indicated by the line 2-2 of Fig. 1.

Fig. 3 is an elevational view of the filling end portion of the casing, showing the holding member for securing the corresponding end cap, and the reservoir thereto.

Referring now more particularly to the accompanying drawings, 5 designates the preferably cylindrical open end reservoir of the pencil which is in the present instance formed of glass, the filling end portion of the reservoir being inwardly offset at 6 adjacent its extremity forming an annular groove in its outer periphery. The distributing end portion of the reservoir is 90 reduced, forming a consequent shoulder 7 adjacent its extremity and fitted over this reduced end portion is a distributing hood 8, preferably of the nature described in the said reissue patent and formed of rubber 95 with a plurality of radial slits 9 in its closed end. The filling end of the reservoir is normally closed by a stopper 10 preferably tapered to fit a corresponding taper of the said end of the reservoir, and being held 100 in the reservoir by a pair of oppositely bowed spring wires 11 yieldably engageable against the inner peripheral shoulder formed at 6.

Fitted about the reservoir is a casing 12 105 which extends from the distributing end of the reservoir to a point inwardly of and adjacent its filling end, and the reservoir

is held against movement to project its distributing ends from the corresponding end of the casing by abutment of its shoulder 7 with an inwardly struck annular shoulder 5 13 of the casing. Between this shoulder 13 and the adjacent end of the reservoir, the casing is taperingly reduced whereby its extremity fits snugly about the hood 8 to thus shield the attaching portion thereof to 10 present a neat and attractive appearance.

10 Inwardly of its shoulder 13, the casing is provided with an outwardly struck annular shoulder 14 which fits over the adjacent end of the casing, to shield the hood 9 when the pencil is not in use, and by limiting the 15 inward movement of this cap on the pencil, compression of the hood 9 to permit possible accidental escape of the contents of the reservoir 13 is prevented.

10 Inwardly of its other end, the casing 12 is provided with an outwardly struck annular shoulder 16 which forms a stop for a filling end closure cap 17 frictionally engageable on said other end of the casing 25 and the end of this cap in the closing position thereof abuts the stopper 10 of the reservoir, to prevent possible displacement of said stopper such as might occur upon jarring movement of the pencil sufficient to displace the spring wires 11. To provide a means for locking this cap 17 on the casing, which means serves also to hold the reservoir against movement with respect to the casing, particularly when the cap is detached, a holding bar 18 is intermediately pivoted to the casing adjacent its shoulder 16 by the passage of a spring piece 19 through an opening 20 in said bar. This spring piece has one end secured by a clip 21 to the casing, and has its other end bearing against the outer face of the bar, and the bar projects outwardly of the end of the casing, and carries at its outer end a ball head 22 which is engageable through an opening 23 in the cap end and which when 45 the reservoir is in normal position in the casing rests within the outer peripheral groove formed at 6 in the reservoir.

Thus upon pressing the inner end of the 50 bar 18, which is curved away from the casing, the head 22 may be retracted to permit the detachment of the cap, and upon releasing the bar the head 22 will frictionally engage the reservoir to hold it against displacement. This bar and spring form a 55 part of a conventional clip, which does not enter into the present invention except with respect to its specific relation with the reservoir and casing, and it will be appreciated that any suitable means for holding the 60 cap, which also possesses the function of holding the reservoir when the cap is removed, can be employed.

With the filling end closure cap 7 in place, 65 the present glue and mucilage pencil com-

prises a compact device capable of convenient manipulation, inasmuch as the filling means of the pencil are entirely shielded. When it is desired to fill the pencil, the cap 17 is removed, the reservoir is drawn partly 70 out of the casing, the stopper 10 is withdrawn either entirely or partly in such manner that it is loosely held by the spring wire 11 to lie at the side of the mouth of the reservoir, and the filling of the reservoir is 75 effected in a ready and exact manner, the reservoir being held in partly projected position by frictional engagement of the locking head 22.

In cold weather it is necessary to heat the 80 reservoir to reduce the fluid therein, and to accomplish this the reservoir is entirely withdrawn from the casing and preferably placed in hot water.

I claim:

1. A mucilage pencil comprising an open end casing, an open end reservoir in the casing, a distributing means at one end of the reservoir, a filling closure at the other end of the reservoir, closure caps for the ends of the casing and means for holding the reservoir in the casing.

2. A mucilage pencil comprising an open end casing, an open end reservoir in the casing, a distributing means at one end of the reservoir, a filling closure at the other end of the reservoir, closure caps for the ends of the casing, means for holding the reservoir in the casing, and the filling closure of the reservoir normally abutting the adjacent closure of the casing.

3. A mucilage pencil comprising a casing, an open end reservoir in the casing, a distributing means at one end of the reservoir, a filling closure at the other end of the reservoir and means for detachably holding the reservoir in the casing.

4. A mucilage pencil comprising an open end casing, an open end reservoir in the casing, a distributing means at one end of the reservoir, a filling closure at the other end of the reservoir and yielding means resisting movement of the reservoir in the casing.

5. A mucilage pencil comprising an open end casing, an open end reservoir in the casing, a distributing means at one end of the reservoir, a filling closure at the other end of the reservoir, a yielding means resisting movement of the reservoir in the casing, and means limiting movement of the distributing means end of the reservoir outwardly from the normally adjacent end of the casing.

6. A mucilage pencil comprising an open 125 end casing, an open end reservoir in the casing, a distributing means at one end of the reservoir, a filling closure at the other end of the reservoir, a detachable closure for the adjacent end of the casing and means 130

for securing the closure to the casing said means being also engageable with the reservoir to hold it in the casing.

7. A mucilage pencil comprising an open end casing, an open end reservoir in the casing, a distributing means at one end of the reservoir, a filling closure at the other end of the reservoir, a cap for the adjacent end of the casing, a spring urged member engageable with the cap to hold it to the casing and said spring urged member being also engageable with the reservoir to hold it in the casing.

8. A mucilage pencil comprising an open end casing, an open end reservoir in the casing, a distributing means at one end of the reservoir, a filling closure at the other end of the reservoir, a cap for the adjacent end of the casing and provided with a recess in its side, a spring urged member carried by the casing and having a head por-

tion engageable in the recess of the cap and said member being also engageable with the reservoir to hold it in the casing.

9. A mucilage pencil comprising an open end casing, an open end reservoir in the casing having one end portion reduced, a distributor hood engaged over said reduced end, means preventing movement of said reduced end of the reservoir outwardly of the normally adjacent end of the casing and said normally adjacent end of the casing being taperingly reduced to fit about the reduced end of the reservoir.

In testimony that I claim the foregoing I have hereunto set my hand at Two Rivers, in the county of Manitowoc and State of Wisconsin, in the presence of two witnesses.

EDWARD C. BERNERS.
